UNITED STATES PATENT OFFICE.

WILLIAM ELLIS, OF SOUTH LAMBETH, ENGLAND.

IMPROVEMENT IN MACHINES FOR CUTTING VENEERS.

Specification forming part of Letters Patent No. 149,732, dated April 14, 1874; application filed March 25, 1873.

To all whom it may concern:

Be it known that I, WILLIAM ELLIS, of South Lambeth, in the county of Surrey, England, engineer, have invented certain new and useful Improvements in Machine for Cutting Veneers, of which the following is a specification:

1. This invention relates to the construction of improved machinery for cutting wood to any required shape, pattern, or design.

2. On the accompanying drawings, Figure 1 represents a front elevation of the improved machine; and Fig. 2, a transverse vertical section thereof through about the line A B, Fig. 1, looking in the direction of the arrow 1.

3. *a* represents the lower part or framing of the machine, above which is bolted, or otherwise secured, oblique standards and slides *b c*.

4. The timber, *d*, to be cut (when raised into and fixed in position, Fig. 2, as hereinafter described) is held by centers *e*, fixed in the inner ends of twin shafts *f*, placed at opposite sides or ends of the machine, and each having one bearing in one of the standards *b*, and the other in one of two end bearings, *g*.

5. The shafts *f* are equally rotated by wheels *h* gearing into mortised pinions *i* on an under shaft, *j*, which runs from end to end of the machine, and receives motion from the primary shaft *k*, on which are placed a fast and a loose pulley, *l m*, by means of a pinion, *n*, and wheel *o*.

6. *p* represents the front or driving shaft of the machine, which receives its motion from the shaft *k* by means of gage-wheels *q*, two of which—namely, those on the shafts *k* and *p*—can be altered at pleasure, (the others being held in arms of a bracket, *q**, which is slotted, and capable of moving upward, downward, or sidewise, so as to accommodate the various-sized wheels which may be placed on *k* or *p*), so as to regulate the speed of the latter shaft, as required. The positions of the wheels *q*, shaft *k*, pinion *n*, and wheel *o* are dotted in Fig. 2.

7. On the shaft *p* are two worms, *r*, (placed immediately in front of the slides *c*), gearing into two wheels, *s*, which, by means of worms *t*, keyed thereto, Fig. 2, work a veneer-knife carrier, *u*, down the slides *c*, together with a broad plate veneer-knife, *v*, causing the same to approach (sidewise) the timber, *d*, to be cut

(and to cut off the outer part of the same in a slice, or as a veneer, as the wood is being rotated, as hereafter described) at a certain definite rate.

8. The knife *v* is set in its carrier in a line with the standards *b*, so that the wood or timber is prevented from springing from the said knife when it is being cut near the center, and consequently the knife will act and cut as solidly with the latter portion as at the commencement with the full timber.

9. But to insure that the heel and toe of the cutting-edge of the knife *v* shall be kept constantly at a uniform angle to the circumference of the block, *d*, being operated upon by it, so that, as the latter is being constantly reduced in diameter by the action of the said knife upon it, the wood shall not be shattered when being cut near the center of the block, but severed therefrom in a continuous and even sheet, I key on the shaft *p* two other worms, *w*, gearing into worm-wheels *x*, which, by means of worms *y*, keyed thereto and passing through swivel worm-boxes *a** in projecting brackets *b** at the under part of the carrier *u*, (centered at *u**) cause that part to receive a slightly quicker motion than the part which receives the descending motion from the worms *t*, as above described, so that the knife *v* constantly alters its position, so as to effect the object desired.

10. On the shaft *p* is also a miter or bevel wheel, *c**, which, by means of other bevel-wheels, *d** *e** (on an inclined shaft, *f**, supported by brackets *f**, projecting from *b* and *c*), and *g**, rotate a top shaft, *h**, on which the latter is, and the bearings of which are carried in brackets *h**, projecting from the back of the standards *b*.

11. On the shaft *h** are two worms, *i**, Fig. 2, (immediately above the standards *b*, and similar in size and distance apart to the worms *r*), gearing into two wheels, *j**, (similar in size and distance apart to the wheels *s*), which, by means of worms *k**, (similar to the worms *t*), actuate V-slides or square rifled flanged blocks *l**, and cause them to descend in the standards *b*, and to carry therewith a hollow longitudinal dovetailed sectional divider, *m**, (of octagonal, hexagonal, or other geometrical figure,) which revolves by contact with the timber to be cut,

and is provided with movable cutting, embossing, impressing, perforating, or other sections n^1 , which are thus caused to approach the wood from above, (at the same time and rate, as the knife v is caused, by the means described, to advance sidewise,) and to cut it longitudinally as it is being rotated.

12. In Fig. 5 (detached view on an enlarged scale) sections of some of the different sections n^1 , which may be made to any pattern required for building or other purposes, are shown. Each section is placed in a dovetailed groove, m^x , in the divider m^1 , and is held fast therein by having a projection at one end pushed into a hole, o^1 , in one of the end plates of the divider.

13. When it is only desired to emboss the wood immediately before it is veneered by the knife v , the divider m^1 is removed from the blocks l^1 , and replaced by an embossing-roller, o^x . (See Fig. 3.)

14. A hollow socket, p^1 , extends below and is bolted to a front plate, q^1 , which is supported by brackets q^3 , and carries the shaft p and its bearings p^x ; and in this socket rotates a short vertical shaft, r^1 , on which are fixed two bevel-wheels, $s^1 t^1$, the former of which gears into and receives motion from the wheel c^1 on the shaft p .

15. A transverse shaft, u^1 , runs below and at right angles to the shaft r^1 the whole width of the machine, and on this are fixed two other bevel-wheels, $v^1 w^1$, Fig. 2, the former of which gears into and receives motion from the wheel t^1 on the shaft r^1 .

16. At right angles to the shafts u^1 and r^1 extends a longitudinal shaft, $s^{\prime\prime}$, which runs in a direction parallel to the shaft j ; and on this shaft, in gear with and receiving motion from the wheel w^1 , is fixed a bevel-wheel, x^1 , Figs. 1 and 2.

17. On the shaft $s^{\prime\prime}$ are placed two worms, y^1 , similar in size to the worms r^w and i^1 , gearing into two wheels, z^1 , similar in size to the wheels s^1 , x^1 , and j^1 , fixed on vertical shafts a^2 , the upper part of each of which is formed into a worm, b^2 , similar to the worms t^1 , y^1 , and k^1 , which actuate slides c^2 , working vertically in the inner sides of the standards b , and carrying a longitudinal slotted shaft, d^2 , on which are secured circular knives e^2 , which can be set to any width of cut or distance apart.

18. By these means the shaft d^2 , with its series of knives e^2 , which are rotated by contact with the timber to be cut, is caused to approach the wood upward, and cut the wood transversely as it is being rotated, at the same time and rate as the longitudinal dividers n^1 and the knife v are caused to approach the same downward and sidewise, respectively.

19. In order to lift the block of wood to its proper position to be acted upon by the series of knives and sections, and so that the centers can be readily and accurately run in to fix the block in position, as hereinafter described, I remove the shaft d^2 , with its dividers e^2 , from its slide-blocks c^2 , and place in the latter cup-

shaped receptacles or elevators f^2 , (see detached view, Fig. 3,) into which, when lowered, the block d can be easily rolled, and then cause the ascent of the blocks c^2 , receptacles f^2 , and block d by means of the wheels v^1 and w^1 on shaft u^1 , and wheel x^1 and worms y^1 on shaft $s^{\prime\prime}$, and worm-wheels z^1 and worms b^2 on shafts a^2 ; but, instead of actuating these means from the shaft p by the wheels s^1 and t^1 on the shaft r^1 , (as is done when causing the ascent of the said blocks c^2 and shaft d^2 , when carrying the knives e^2 and acting on the wood,) I disconnect the wheels t^1 and v^1 by means of a clutch-lever, g^2 , and actuate them from an independent shaft, h^1 , supported in bearings h^{1x} , and bevel-wheels i^2 and j^2 , placed in front of the machine, and operated by a belt and pulley, l^2 ; and after it is thus lifted, I run the centers e in, as herein-after described, and so fix the block, and then reverse the motion of the pulley l^2 in a similar manner, as described hereafter in respect to the pulley l^2 , cause the descent of the blocks c^2 and receptacles f^2 , and remove them from the blocks and replace the shaft d^2 , and disconnect the wheels i^2 and j^2 by means of a clutch-lever, m^2 , and again connect the wheels v^1 and t^1 by the lever g^2 , and run the shaft d^2 and knives e^2 up to the block d , when the apparatus will be in readiness to commence acting upon the block.

20. When the block has been lifted into position by such means, the centers e are readily and accurately run in, so as to fix it in position, in the following manner:

21. I make the bearings g at each end of the machine very solid and compact, so as to be capable of withstanding with ease a considerable lateral thrust, and provide worms n^2 , which work in the bearings g , and provide one of the worms with a manual or hand wheel, o^2 , and the other with a toothed wheel, p^2 , which gears into a pinion, q^2 , on an independent shaft, r^2 , supported in brackets s^2 , bolted or otherwise secured to the foundation or floor.

22. Upon the shaft r^2 I also place three pulleys, t^2 , the outer ones of which run loose, while the middle one is fast.

23. Upon one of the outer pulleys works a straight band, u^2 , and upon the other a crossed band, v^2 , so that the in or out motion of the twin shaft f at this end of the machine depends upon which of the bands is placed upon the fast pulley. If the straight one is, the shaft f is caused to run in and fix the centers e in the wood; but if the crossed band is, the shaft is caused to run out, or vice versa.

24. The twin shaft f at the other or driving end of the machine and its center e are stationary, so that the block d is thrust thereon and centered at both ends at once. It is, however, capable of being actuated by its hand-wheel o^2 in case a block of short length should be placed in the machine, so as to run its center up to position.

25. The thickness of the veneer is gaged by a rest-bar, b^3 , secured to sliding holding-pieces c^3 by small nuts d^3 , and regulated by hand-

screws e^2 , which allows the knife v to cut the veneer to the required thickness only.

26. In order to prevent any hard pieces of wood or any obstruction choking between the knife v and the bar b^3 , and to allow them to pass, I place at the rear of the bar b^3 two or more springs, f^3 , so that it is enabled to give slightly and allow any such obstructions to pass; and, in addition, I provide two or more pressure-rollers, g^3 , fitting in slots in the rear of the bar b^3 , to diminish the friction on the cut wood as it emerges from the machine, and to receive the pressure, so that the pattern on the wood is effectually preserved.

27. When the machine is employed for cutting laths I cause the latter to fall into two or more receivers, h^3 , fitted to the front of the carrier u , the contour of which they follow, and, on turning round and over the same, are completely separated, when they fall onto an endless traveling belt, i^3 , and are carried away thereby to any place for securing them in bundles.

28. The action of the machine is as follows: Motion being given to the primary shaft k by the pulley l , is communicated, by the pinion n and wheel o , to the shaft j , which rotates the pinions i , and these, by means of the wheels h , impart the motion to the twin shafts f . The wood d , being fixed between the centers e , consequently receives the motion from the shafts f , and is caused to rotate, and is first cut transversely by the knives e^2 , and then receives longitudinal cuts, holes, impressions, or designs from the sections n^1 of the top or longitudinal divider m^1 , and is, lastly, cut as a veneer by the knife v , and passes thence over the carrier u , and into a space or hole, j^3 , in front of the machine, and is there collected or carried away by the belt i^3 , as required.

29. The motion is also communicated by the wheels g , from the shaft k , to the shaft p , and thence, by means of the worms r and w , wheels s and x , and worms t and y , to the carrier u and knife v .

30. And is further communicated from the shaft p , by the wheels $c^1 s^1 t^1 v^1 w^1 x^1$ and worms y^1 , on their respective shafts, and wheels z^1 , and worms b^2 , to the slides c^2 , shaft d^2 , and

knives e^2 , and also, by the wheels $d^1 e^1 g^1$ and worms i^1 on their respective shafts, wheels j^1 , and worms k^1 , to the blocks l^1 and divider m^1 , so that, (as the shafts p , s^1 , and h^1 are thus all rotated at an equal speed,) while the wood is being rotated, as above described, the transverse dividers, the longitudinal dividers or embossing-roller, and the veneer-knife are caused to approach the continually-decreasing circumference of the wood, all at the same time and rate, and in exact proportion as the wood is being diminished by them, by the means above described and immediately above referred to, until it is entirely cut up into the articles required, after which the machine is brought back to its original position, before starting on a fresh block, by means of a fast reversing-pulley, l^3 , on the shaft p .

I claim—

1. The combination, in a veneer or lath cutter, of the shafts for retaining and rotating the log, and the cutters o , m^1 , and e^2 , which are simultaneously fed toward the center of the log by devices substantially as described.
2. The combination of the shafts $f f$, the cutter m^1 , and shafts, screws, worms, and gear herein described, for operating the said cutter.
3. The combination of the shafts $f f$, elevating-screws, blocks c^2 , and elevators f^2 , substantially as and for the purpose set forth.
4. The rotating shafts $f f$, rendered longitudinally adjustable, as specified.
5. The combination of the knife o , feedingscrews t , and regulating-screw y , as set forth.
6. The combination of the knife o , carrier u , recesses h^3 , and traversing bands j^3 , as and for the purpose set forth.

In testimony whereof I have signed my name to this specification in the presence of two subscribing witnesses.

WM. ELLIS.
